UNITED STATES PATENT OFFICE.

FREDERICK O. REICHARDT, OF MARIETTA, OHIO.

VENTILATOR.

Application filed April 5, 1922. Serial No. 549,678.

To all whom it may concern:

Be it known that I, FREDERICK O. REICHARDT, a citizen of the United States, residing at Marietta, in the county of Washington and State of Ohio, have invented certain new and useful Improvements in Ventilators, of which the following is a specification.

This invention relates to improvements in ventilators for windows and has as one of its primary objects to provide a ventilator which may be adjusted for disposal within window frames of various widths and which when arranged in place will be securely held and extend completely across the opening afforded by the partly elevated sash.

Another object of the invention is to provide a simple and conveniently operable means for adjusting the ventilator to the window frame and which means will provide for the even and corresponding adjustment of the movable sections of the ventilator through the manipulation of a single operating means so that after the ventilator has been disposed within the window opening it may be readily expanded to the required width to fill the opening.

Another object of the invention is to provide a novel construction whereby the ventilator may be made substantially in its entirety from sheet metal and simple and inexpensive fittings.

A further object of the invention is to provide a novel arrangement of slats and a novel means whereby the slats may be adjusted to control the passage of air through the ventilator screen, and securely retained in positions of adjustment.

In the accompanying drawings:

Figure 1 is a perspective view of a ventilator constructed in accordance with the invention arranged within a window frame;

Figure 2 is a perspective view of the ventilator removed from the frame, parts being broken away and parts being shown in section;

Figure 3 is a group perspective view illustrating a number of component parts of the structure disassembled;

Figure 4 is a detail vertical front to rear sectional view through the ventilator illustrating particularly the slats and their adjusting means;

Figure 5 is a group perspective view illustrating certain elements of the means

provided for adjusting the movable or adjustable sections of the ventilator;

Figure 6 is a similar view illustrating certain elements of the adjusting means for the slats;

Figure 7 is a detail horizontal sectional view on the line 7—7 of Figure 2; and

Figure 8 is a view similar to Figure 4 illustrating a modified arrangement of the slats and the adjusting means therefor.

Generally speaking the ventilator embodying the invention comprises an intermediate or main section which is indicated in general by the numeral 1, and end sections indicated in general by the numeral 2, means being provided for adjusting the end sections with relation to the intermediate section so as to expand or contract the ventilator as a whole and thus adapt the same for disposal within window frames of various widths.

The intermediate or main section 1 of the ventilator comprises a frame-like structure including an upper rail, a lower rail, and end stiles indicated in general respectively by the numerals 3, 4 and 5. These several parts are formed from sheet metal. The upper rail 3 comprises a vertically disposed portion 6, a horizontally disposed portion 7 which extends inwardly or rearwardly at right angles from the plane of the portion 6, a portion 8 which extends longitudinally of the edge of the portion 7 and upwardly at right angles with relation to the plane thereof, and a flange 9 which projects inwardly or rearwardly at right angles from the plane of the portion 8 and extends along the upper edge thereof and has its free edge portion turned downwardly and forwardly as at 10. The portion 8 is designed, in the use of the ventilator, to seat against the inner side of the bottom rail of the window sash when the sash is lowered to position resting upon the portion 7 of the rail 3 thus insuring of a closing of any space that might otherwise exist between the sash and the top of the ventilator. The numeral 11 indicates an apron portion which depends from the lower edge of the vertically disposed portion 6 and is inclined in the manner shown in Figures 3 and 4 of the drawings and provided between its ends with a recess indicated by the numeral 12.

The upper rail 3 of the frame structure of the intermediate section further includes

2
a face plate 13 which is secured in any suitable manner as for example by rivets 14 to the rear face of the portion 8 of the previously described section of the top rail, and 5 is provided midway between its ends with a recess 15 located opposite the recess 12 in the apron 11. The lower edge portion of the plate 13 is turned back upon itself to provide a flange 16 which anchors the upper 10 edge of a foraminous screen 17 of wire mesh or similar material.

The bottom rail 4 comprises a rail section 18 having a vertically disposed portion 19 and an upwardly and rearwardly inclined 15 portion 20 provided along its upward edge with an upwardly and forwardly inclined flange 21, the portion 19 being likewise provided along its lower edge with a flange 22 adapted to rest flat upon the sill of the 20 window frame within which the ventilator is arranged. The said bottom rail further includes a rail section indicated by the numeral 23 and in the nature of a face plate which is disposed parallel to the plate 13 25 and in a plane therewith and provided along its lower edge with an inwardly projecting flange 24 presented edgewise to the flange 22. The upper edge portion of the plate 23 is bent upon itself to provide a flange 25 30 securing the lower edge of the foraminous screen 17.

Bracket members 26 are secured to the inner or rear face of the member 6 of the top rail and extend across the space between 35 said member and the face plate 13 and are likewise secured to the said plate so that the plate is braced at its intermediate portion, with relation to the said member 6. In a like manner brackets 27 are 40 provided upon the member or section 18 of the lower rail 4 and are secured thereto and to the face plate 23 to relatively brace these parts. The wire screen fabric 17 will of course be more or less tautly stretched 45 between the upper and lower rails of the frame structure.

Each of the stiles 5 comprises an intermediate or web portion indicated by the numeral 28 and provided at its vertical edges 50 with flanges 29 occupying parallel planes at right angles to the plane of the web 28. The stiles 5 are disposed at their upper and lower ends respectively between the member 6 and face plate 13 of the upper rail and the member 18 and face plate 23 of the 55 lower rail and their flanges 29 are secured to these parts by riveting or otherwise. The web 28 of each stile 5 is preferably formed with a longitudinal bend 30 extending 60 throughout its entire height and providing a portion 31 offset with relation to the other portion of the said web.

The structure above described completes 65 the main or intermediate section of the ventilator except for the slats which are mount-

ed within the frame structure and operated by a means and in a manner to be presently set forth.

Each of the end sections 2 of the ventilator comprises spaced front and back plates indicated respectively by the numerals 32 and 33, one of the plates as for example the front plate 32 having its upper end portion bent over at right angles as at 34 and secured to the adjacent side of the plate 33. The numeral 35 indicates a bracing member which is disposed and secured between the laterally outer edge portions of the plates 32 and 33, this bracing member preferably comprising an intermediate portion or web 36 and side flanges 37 which latter are riveted, welded, or in any other manner secured to the said edge portions of the plates 32 and 33. The plates 32 and 33 are so spaced with relation to each other that the end sections 2 are adapted, as a whole, to slidably fit over the ends of the frame structure of the intermediate or main section 1. In this manner the end sections 2 are adapted to be slidably adjusted upon and with relation to the ends of the main or intermediate section 1 and when properly adjusted are designed to seat at their outer vertical sides against the stiles of the window frame within which the ventilator is disposed. In order to prevent displacement of the end sections with relation to the intermediate section, it is preferable that the upper end of the plate 33 be extended above the portion 34 of the plate 32 and provided with a right angularly bent tongue 33' designed to slidably engage beneath the portion 9 of the top rail section 6 and behind the flange 10 thereof. The means provided for adjusting the sections 2 includes tubular slides 38 which are arranged in axial alignment with each other and threaded or otherwise secured at their relatively remote ends in sockets or bosses 39 upon bracket plates 40 in turn secured to the inner sides of the intermediate portions 36 of the respective bracing members 35. The tubular slides 38 fit freely through openings 41 formed in the upper end portions of the stiles 5 and are provided at their relatively adjacent ends with ferrules 42 interiorly threaded for the reception of the oppositely threaded ends of an adjusting screw rod 43, the threads of this rod being right and left hand and the rod being provided midway between its ends with a knurled finger wheel 44 by which it may be conveniently rotated. The bracket members 26 are provided with slots or recesses 45 in which the tubular slides 38 are rotatably and slidably received, the slides being in this manner guided and braced during adjustment. By reference to Figure 4 it will be evident that a portion of the periphery of the finger wheel 44 projects through the recess 15 in 120

the face plate 13 to such an extent as to render the wheel readily accessible for the purpose of rotating the same to correspondingly rotate the adjusting screw rod 43 and 5 thus draw the tubular slides 38 toward each other or move them apart and correspondingly adjust the end sections 2 with which these slides are associated.

In that form of the invention illustrated 10 particularly in Figure 4, the slats are indicated in general by the numeral 46 and are preferably formed of sheet metal, and each slat comprises a flat body portion 47 having a flange 48 extending along its upper edge 15 and a flange 49 extending along its lower edge. The flanges 48 and 49 lie approximately at right angles to the plane of the body portion 47 of the slat and extend in opposite directions from said plane 20 and in the assembled relation of the slats, and when the slats are closed as shown in the said Figure 4, the upper flange 48 of one slat will overlap or overlie the lower flange 49 of the slat next above it. The 25 slats are provided at the ends of their body portions 47 with flanges 50 which project in the same general direction as the flanges 48 and 49 and which are pivotally connected at their upper ends as at 51 to the offset portions 31 of the respective stiles 5. Bars 52 are arranged at the ends of the slats 46 and are pivotally connected as at 53 to the lower ends of the flanges 50. It will now be evident 30 that an upward and forward swinging movement of any one of the slats 46 as for example the uppermost slat, will result in a corresponding movement of the other slats because of their mutual connection through the medium of the bars 52. Therefore, as a 35 means for adjusting the slats, a link member 54 is pivotally connected at its lower end as at 55 to the forward side of the said uppermost slat near the lower edge of the latter and at its upper end is pivotally connected as at 56 to an adjusting yoke 57 comprising spaced arms 58 which straddle the finger wheel 44 and are connected as stated to the upper end of the link 54. The yoke 40 also includes a stem 59 which is preferably flat upon one side and is disposed with its 45 said side resting in contact with the inner surface of a cap plate 60 which is secured upon the rear face of the face plate 13 and covers the opening 15. This cap plate is 50 provided with a slot 61 to receive the projecting peripheral portion of the finger wheel 44, and below this slot is formed with a vertically extending slot 62 through which 55 slidably projects a threaded stud 63 carried 60 by the stem 59, a binding nut 64 being threaded onto this stud and adapted to be tightened against a washer 65 disposed between it and the cap plate 60 and thus draw 65 the stem 59 tightly against the said cap plate to secure the yoke 57 in positions of adjust-

ment. The link 54 is housed between the face plate 13 and the section 6 of the top rail and depends through the recess 12 in the apron 11. It will now be evident that by loosening the binding nut 64, the yoke 57 may be slid upwardly or downwardly 70 beside the cap plate 60 so as to adjust the slats 46 and after the desired adjustment has been effected, the nut is to be tightened so as to bind the yoke against the cap plate and 75 thus maintain the slats in their adjusted position. Inasmuch as the spaced arms 58 of the yoke 57 straddle the finger wheel 44, the yoke constitutes also a means for preventing longitudinal play of the adjusting screw rod 80 43 and the slides 38 which are connected thereby. Consequently the adjustable end sections 2 are held more or less rigidly in the 85 positions to which they are adjusted through rotation of the said finger wheel. It is to be noted that the yoke 57 performs this secondary function without in any way interfering with adjustment of the yoke to effect adjustment of the slats.

In that form of the invention shown in 90 Figure 8 of the drawings the structure is substantially identical with that previously described except that in this instance a single bar 66 is pivotally connected to outstanding ears 67 upon the lower flanges 68 of the 95 slats 69.

Ordinarily it will be found sufficient to provide a single adjusting means such as the slides 38, adjusting screw rod 43, and finger wheel 44, for adjusting the end sections of the ventilator and this adjusting means will preferably be located at the top of the structure. However if the ventilator is of exceptional height, it may be found necessary to duplicate this structure at the 100 lower portion or bottom rail of the ventilator so as to provide for an even adjustment of the upper and lower ends of the 105 ends 2. Likewise the structure may be modified in various other respects if found 110 expedient because of variations in the sizes in which the device will be manufactured.

Having thus described the invention what is claimed as new is:

1. In a ventilator, a main section, end sections slidably assembled therewith, and means operable to adjust the said end sections longitudinally with relation to the main section, said means comprising a rotatable threaded adjusting rod, and members connected with the end sections and having threaded engagement with said rod, the said rod and the said members associated therewith being housed within a part of the main section and the rod carrying an operating member having a portion extending exteriorly of the said part of the main section.

2. In a ventilator, a main section, end sections telescopically fitting the ends of the 130

main section and adjustable to provide for expansion and contraction of the ventilator as a whole, and means operable to adjust the said end sections, the main section including a top rail having an upstanding portion to rest against the face of the lower rail of a window sash and provided with an overhanging and inturned flange to provide a channel, the said end sections having portions slidably interlocking with the said flange.

3. In a ventilator, a frame including upper and lower rails and end stiles, slats pivotally mounted at their ends upon the said stiles and extending between the same within the frame, means connecting the slats for movement in unison upon their pivots, and means operatively connected with one of said slats for angularly adjusting the same about its pivots, the said adjusting means comprising a plate member upon one of said rails, a member vertically adjustable with relation to said plate member, the plate member having a slot extending in the direction of adjustment of the said member and the member having a stud projecting through the slot, a nut threaded upon the stud for coaction with the plate member to hold the adjustable member in positions of adjustment, and a link connected with the said adjustable member and with one of said slats.

4. In a ventilator, a main section, end sections slidably assembled therewith, slats pivotally supported for angular adjustment within the main section, a member adjustably mounted upon an intermediate portion of the main section and having operative connection with the slats to effect angular adjustment thereof when the said member is adjusted, the member including spaced

portions, a threaded adjusting rod extending transversely with relation to the spaced portions of the member, an operating finger wheel upon the said rod confined between the spaced portions of the said adjustable member, and operative connection between the oppositely threaded ends of the rod and the said end sections for effecting adjustment of the latter when the rod is rotated through the medium of the said finger wheel.

5. In a ventilator, a main section, end sections slidably fitted upon the ends of the main section, the main section comprising upper and lower rails and stiles connecting the rails, the lower rail consisting of parallel plates, one of said plates having a transversely directed upper portion and a flange at the upper edge of said transversely directed portion arranged reversely thereto, slats pivotally mounted on and extending between the stiles, the lowermost slat having a flange to engage under the first-mentioned flange, means for angularly adjusting the slats, and means for adjusting the end sections longitudinally of the main section.

6. In a ventilator, a main section, end sections slidably fitted upon the ends of the main section, the main section comprising upper and lower rails and stiles connecting the rails, the upper rail consisting of parallel plates, one of said plates having a transversely directed lower portion, slats pivotally mounted in and extending beneath the stiles, the uppermost slat having a flange adapted to engage over said transversely directed portion of the upper rail, means for angularly adjusting the slats, and means for adjusting the end sections.

In testimony whereof I affix my signature.

FREDERICK O. REICHARDT. [L.S.]
